UNITED STATES PATENT OFFICE.

BRADLEY W. RUMBARGER, OF FAIRBANKS, LOUISIANA, ASSIGNOR TO SOUTHERN CARBON COMPANY, OF FAIRBANKS, LOUISIANA, A CORPORATION OF DELAWARE.

METHOD OF PRODUCING CARBON-BLACK.

1,401,737.

Specification of Letters Patent. Patented Dec. 27, 1921.

Application filed October 5, 1920. Serial No. 414,891.

To all whom it may concern:

Be it known that I, BRADLEY W. RUMBARGER, a citizen of the United States, and a resident of Fairbanks, in the parish of 5 Ouachita and State of Louisiana, have invented certain new and useful Improvements in Methods of Producing Carbon-Black, of which the following is a specification.

10 My invention relates to that method of producing carbon black in which carbon is liberated by the imperfect combustion and decomposition of a hydrocarbon compound, preferably in some fluid form, as for instance hydrocarbon gas or vapor, the carbon so liberated being deposited upon a suitable plate or surface from which it is subsequently removed by scraping or otherwise.

15 20 My invention will be particularly described in connection with the process of producing carbon black from the unburned and decomposed portion of a hydrocarbon gas or vapor fed through a suitable burner suitably housed or inclosed, from which its application to the production of carbon black and other hydrocarbon fluids will be readily understood.

It has been proposed to produce carbon 30 black by burning natural gas hydrocarbon vapors or other allied or analogous products or substances in an incomplete supply of oxygen or air, the burner or burners being for that purpose usually located in a 35 suitable housing or inclosure and being arranged so that the flame will impinge upon a suitable plate or surface upon which the carbon black collects. In this operation the carbon collected is not the direct result of 40 the combustion of the hydrogen through union with the oxygen supplied from the air or otherwise to maintain the flame but is the direct result of the decomposition of the unburned portion of the hydrocarbon by 45 the heat of the flame or burning portion of the material and will result primarily from the inner part of the flame or jet where the oxygen supply is low but where the heat is sufficient to break up the hydrocarbons 50 present.

The aim of my present invention is to so conduct the above operation of producing carbon black that a more effective or extensive decomposition and deposit of car-

bon black may be secured to which end my 55 invention consists essentially in protecting the carbon producing flame or jet by a gaseous screen or curtain preferably surrounding the same and adapted to exclude or cut off the supply of oxygen, said screen being 60 preferably a flame of any burning material. For convenience a hydrocarbon may be supplied to maintain the said protective flame or screen.

By this means I secure a greater decom- 65 position of the hydrocarbons owing to the lack of oxygen and the presence of heat from the protecting screen.

My invention consists also in the construction 70 of burner adapted particularly for carrying on the improved process as will be hereinafter more particularly described.

Figure 1 of the drawing shows in vertical section a typical form of apparatus adapted 75 for practicing my invention.

Fig. 2 is a plan of the burner and shows the relation of the carbon producing and surrounding protective flames to one another. 1 is the plate or body upon which the carbon black is deposited. 2 is the body of 80 the burner and 3 the hollow center to which the hydrocarbon in gaseous or liquid form may be supplied for egress through suitable 85 burner tips or jets. In the particular form of my invention shown there is a central jet or jets 4 supplying the inner carbon producing flame and 5 is a jet or jets furnishing a flow by which a surrounding flame or flames may be produced to form a screen 90 limiting the access of oxygen to the central flame and also to furnish heat assisting in the decomposition of the hydrocarbon supplied by the inner jet. Obviously the burner may be of any desired size as may be deemed convenient or desirable and any 95 number of inner carbon producing jets may be maintained as likewise any number of outer or protective jets or flames.

Also as will be obvious the flames will be graduated or adjusted by the size or number of the jet orifices or by any other desired expedient, to produce the effect described.

In addition each burner of the plant may have an outer protective wall 6 adapted to 105 prevent access of oxygen in undesirable or unnecessary amount to the burner. The building or inclosure in which the burners

or burners and the collecting plate are housed may be of any desired form or construction as well understood in the art.

What I claim as my invention is:—

- 5 1. The herein described improved method of producing carbon black from a flame of hydrocarbon consisting in conducting the operation while said flame is surrounded by a protective gaseous screen adapted to 10 exclude oxygen.
- 15 2. The herein described improvement in producing carbon black from a flame of hydrocarbon consisting in burning hydrocarbon behind a supplemental flame forming a protective gaseous screen adapted to 20 exclude oxygen from the black producing flame.
- 20 3. The herein described improvement in producing carbon black from a hydrocarbon flame consisting in maintaining a protective flame forming a gaseous screen exterior to and surrounding said flame and adapted to

exclude oxygen therefrom during the carbon producing operation.

4. A burner for producing carbon black 25 having the usual carbon black collecting plate and black producing jet associated therewith and provided with a flame producing jet or jets producing an oxygen excluding protective gaseous screen surround- 30 ing the black producing jet.

5. A burner for carbon black having a jet or jets producing a flame forming an oxygen excluding screen surrounding the carbon producing jet and an exterior protective wall. 35

Signed at Monroe, in the county of Ouachita and State of Louisiana, this 16th day of September, A. D. 1920.

BRADLEY W. RUMBARGER.
